KNIFE-BLADE SWITCH.

1,354,525.

Specification of Letters Patent.

Patented Oct. 5, 1920.

Application filed July 15, 1918. Serial No. 244,940.

To all whom it may concern:

Be it known that we, ALEXANDER H. TRUMBULL and TONJES A. BOTH, citizens of the United States, residing at Stratford, county of Fairfield, State of Connecticut, have invented an Improvement in Knife-Blade Switches; of which the following is a specification.

This invention has for its object to produce a knife blade switch which has been entirely reorganized and reconstructed in order to overcome objections that have been found to exist in all switches of this type now upon the market, and to provide a switch which shall be relatively inexpensive, extremely durable, easily adaptable to feed wires leading in from above or below, which shall have a quick break and shall provide the maximum of safety when required to carry a current of high voltage.

With these and other objects in view we have devised the novel switch of which the following description in connection with the accompanying drawings is a specification, reference numerals being used to indicate the several parts.

Fig. 1 is a plan view, the parts being in the circuit closing position;

Fig. 2 a side elevation corresponding therewith;

Fig. 3 a section on the line 3—3 in Fig. 1, looking in the direction of the arrows;

Fig. 4 a perspective view of parts disassembled, illustrating our novel mode of connecting the blades to the cross bar;

Fig. 5 a partial side elevation showing the contact blades in a position an instant before the circuit is opened;

Fig. 6 a perspective view of parts disassembled, illustrating the construction of one of the auxiliary contact blades;

Fig. 7 a perspective view of parts disassembled, illustrating our novel mode of connecting the blades to the jaws; and

Fig. 8 is a plan view illustrating slight changes in the details of construction.

10 denotes the base, 11 binding screws for the feed wires, 12 binding screws for the circuit wires, 13 the jaws or posts, 14 the blades, 15 the auxiliary blades, 16 the cross bar to which the blades are attached, 17 the fuses and 18 the fuse clips.

In most States it is required that the fuses be located between the feed wires and the contact jaws. That, however, is unimpor-

tant so far as the present invention is concerned. In all States, however, it is required that the blades swing downward in opening the circuit. This is in order to prevent accidental closing of the circuit which might result if the blades could drop to the circuit closing position, the requirement being for a full upward swing of the blades in order to close the circuit. As the leading in or feed wires are likely to come from either above or below, it is desirable that the elements we have indicated by 13 should be adapted to serve either as contact jaws or as carrying posts for the blades. In the drawings the binding screws 11 for the feed wires are shown in position to receive the feed wires from below. Feed wire binding screws 11 are shown as connected to the lower fuse clips by current carrying strips 19, the upper fuse clips as connected to the lower jaws or posts by strips 20, and the upper jaws or posts as connected to the circuit binding screws 12 by strips 21.

While it should be understood that the elements indicated by 13 are adapted to serve either as contact jaws or as blade carrying posts, we shall for convenience in description refer to them as jaws. Four pairs of jaws are required, each pair being formed from a strip of metal bent at right angles on opposite sides of its midlength, the two jaws being then bent obliquely toward each other and then parallel, the upper end of each jaw on the side toward the opposite pair of jaws, being caused to flare outward slightly for convenience in making contact with the blades. The jaws are attached to the base by screws 22.

The novelty of the jaws is comprised in the tension device. The tension device ordinarily used consists of a bolt, passing through the jaws and provided with a nut and spring washer, and when the blades are reversed these parts are transferred to the other set of jaws. An important feature of our invention is to provide a permanent tension device in each post or pair of jaws, which will leave the jaws free to adapt themselves to the blades and always provide a springy contact. This is a great improvement on the tension devices heretofore in use and moreover costs little, requires no shifting of parts and is not in the way when the blades are reversed and the parts that previously served as contact jaws are utilized as 110

blade carrying posts. This result we accomplish by means of spring tongues 23 which are cut out from metal of the jaws and are provided with a cross connection 50, as a rivet or set screw extending between the tongues. Where rivets are used, as in Fig. 5, the rivets are of course headed at each end, one end only being shown. Where set screws are used, as in Figs. 2 and 3, the set screws 5 pass freely through one tongue and have threaded engagement with the other, so that if required the tension may be adjusted at any time. Ordinarily, however, no adjustment of the tension is required when the 15 blades are reversed, or under the ordinary conditions of use. The tongues are made sufficiently long to provide ample resilience and at their sides and one end are completely detached from the jaws, the separating cuts being made wide enough to prevent any contact between the tongues and the surrounding walls of metal.

The blades are detachably connected to the set of jaws serving as posts in a novel manner which permits quick attachment and detachment and without the use of screws. 25 The jaws are provided with holes 24 and the attaching end of each blade with a hole 25. The end of each blade is placed between a pair of jaws with the holes in alinement. A pin 30, having a sliding fit, is passed through the holes in the blade and the jaw, and is retained in place by a clip of peculiar construction. This clip, see Fig. 7, is made of 30 spring metal and consists of spring arms 26 which are adapted to clasp the blade, see Figs. 1 and 2. Each of the spring arms has extending therefrom another spring arm 27. The free end of each spring arm 27 is provided with a head 28 at the center of which is a shallow cup 29. The inner concave faces of these cups engage the ends of the pin and retain it in place. The edges of the cups bear against the outer faces of the 40 jaws and hold them against the blades with sufficient pressure to retain the blades in any position in which they may be placed. The clip, however, may be readily slipped off and on when it is required to reverse 45 the blades.

The free ends of the blades in all switches of this type are connected by a cross piece which is usually made of fiber or molded to the required shape. Molded cross pieces 55 are brittle and are easily broken unless made unreasonably large and unless made of expensive material frequently soften and warp when a poor contact is made. Another objection to solid cross bars is that the screws or rivets by which they are connected to the blade are exposed and are live parts when the circuit is closed. The result is that the operator may get a shock in operating the switch unless great care is used, or 60 in the fully open position should a fuse 65

blow out. These objections we overcome by a novel construction of parts which permits an inside attachment of the blades to the cross bar, thus completely insulating the connecting means and avoiding any possible 70 danger of shock, and enabling the knob or handle to be dispensed with if preferred, which is quite desirable under certain conditions.

16 denotes the insulating cross bar which 75 is tubular, and is provided near its ends with slots 31. The backs of the blades are provided at their jaw engaging ends with ears 32 adapted to pass through the slots and into the tubes, the ears being provided with 80 shoulders 33 which engage the ends of the slots. 34 denotes internally threaded plugs which are driven into the ends of the tubes past the slots with a drive fit. The ears are provided with holes 35. Screws 36 pass 85 through these holes without threaded engagement and are turned into engagement with the threaded holes in the plugs, thus locking the blades and the cross bar rigidly together with a wholly concealed and insulated connection. This cross bar may contact with the ends of the jaws in the circuit closing movement and serve as a stop for the movement of the blades, and may also contact with the lower fuse clips in the open 90 circuit position. 37 denotes a knob or handle which is ordinarily provided but is not necessary as the cross piece provides a smooth and safe grip for the hand.

In order to insure a quick break, we provide 100 the auxiliary blades 15, which are of novel construction and are attached to the blades in a novel manner, the spring being wholly concealed. Each auxiliary blade is blanked out from sheet metal and folded 105 upon itself. The exact thickness of the metal used is immaterial but as the auxiliary blades must be of uniform thickness with the blades we preferably use for the auxiliary blades metal of approximately half 110 the thickness of the blades. The attaching end of each auxiliary blade is provided with ears 38, which are adapted to lie on opposite sides of the blade, to which the auxiliary blade is secured by a pivot pin 39 which 115 passes through holes in the ears and the blade. Between the ears is a socket 40 in which the spring 41 is housed. This spring is a coil carried by a pin 42, which passes through the walls of the socket, and is provided with extended ends 43, one of which bears against the under side of the blade and the other against the bottom of the socket in the auxiliary blade, the normal action of the spring being to retain the top of the 120 auxiliary blade in close contact with the under side of the corresponding blade 14, compare Figs. 4 and 5.

In moving the blades to the circuit closing position, the auxiliary blades of course 125

take the load first and pass it to the blades. As the meeting faces of the blades and the auxiliary blades are in close contact, the passage of the current is not limited to the hinge connection between the blades. In opening or breaking the circuit the action is as shown in Fig. 5. The blades will first pass out of engagement with the jaws leaving the auxiliary blades, however, in engagement with the jaws. The circuit will remain closed until the ends 44 of the auxiliary blades, through the upward movement of the blades while the auxiliary blades remain in engagement with the jaws, are brought into engagement with the under side of the blades, as in Fig. 5. The raising movement of the blades has of course been against the power of springs 41. When the ends of the auxiliary blades come into engagement with the under side of the blades, continued movement of the blades will draw the auxiliary blades out of engagement with the jaws, and the springs will cause the auxiliary blades to break the circuit with a snap, the auxiliary blades instantly returning to their normal position, in close contact with the blades, as in Fig. 4.

The form illustrated in Fig. 8 differs only in details of construction. The clips which retain the blade pins in place and press the arms of the jaws against the blades are carried by the jaws instead of by the blades. In this form we use a U-shaped clip, comprising simply arms 45 provided at their free ends with heads 46 which correspond in every respect with the heads 28 and cups 29 of the other form, the additional spring arms by which the heads are carried in the other form being dispensed with. The attachment of the free ends of the blades to the tubular insulating cross piece differs in that the cross piece is attached to the ends of the blades and lies in approximately the same plane as the blades, instead of being secured to the tops of the blades and lying above them. We have also shown the plugs 48 within the cross piece as lying outside the ears 49 at the ends of the blade instead of on the inner side of the ears as in the other form. In the present form the screws 47 pass through the plugs without threaded engagement and have threaded engagement with the ears. The knob or handle in this form is shown as attached in such a manner as to project forward from the cross piece, instead of lying above the cross piece as in the other form.

Having thus described our invention, we claim:

60 1. In a switch of the character described, two sets of jaws, each set consisting of two pairs of jaws provided with means enabling them to serve either as blade carrying posts or as contact jaws, each pair of jaws being formed from a strip of metal bent at right

angles at opposite sides of its midlength, the jaws being then bent obliquely toward each other and then parallel, each jaw having a tongue cut out from the parallel portion thereof, a cross connection in each pair of 70 tongues, and blades pivotally connected to one set of jaws and adapted to engage the other set to close the circuit.

2. In a switch of the character described, two sets of jaws formed from strips of sheet 75 metal bent to shape, each set consisting of two pairs of jaws provided with means enabling them to serve either as blade carrying posts or as contact jaws, blades pivotally connected to one set of jaws and 80 adapted to engage the other set to close the circuit, and each pair of jaws being provided with tongues cut out from the metal thereof and a cross connection engaging the tongues, to provide a tension for the jaws. 85

3. Jaws of the character described formed from a strip of sheet metal bent to shape, each jaw being provided with a tongue cut out from the metal thereof, and a cross connection engaging the tongues, substantially 90 as described for the purpose specified.

4. In a switch of the character described, two pairs of jaws, each pair being provided with means enabling it to serve either as a blade carrying post or as contact jaws, holes 95 in alignment in each pair of jaws, a blade having at its attaching end a corresponding hole, a pin adapted to engage said holes and a spring clip having heads which engage the jaws and retain the pin in place. 100

5. In a switch of the character described, two pairs of jaws, each pair being provided with means enabling it to serve either as a blade carrying post or as contact jaws, a blade, a pin extending through one pair of 105 jaws and the blade, and a detachable spring clip for retaining the pin in place.

6. In a switch of the character described, two pairs of jaws, each pair being provided with means enabling it to serve either as a 110 blade carrying post or as contact jaws, a blade, a pin extending through one pair of jaws and the blade, and a detachable spring clip for retaining the pin in place, said clip being provided with means for attachment 115 to the blade.

7. In a switch of the character described, two pairs of jaws, each pair being provided with means enabling it to serve either as a blade carrying post or as contact jaws, a 120 blade, a loose pin extending through one pair of jaws and the blade, and a detachable spring clip adapted to engage the jaws and having heads provided with cups which receive the ends of the pin. 125

8. In a switch of the character described, two pairs of jaws, each pair being provided with means enabling it to serve either as a blade carrying post or as contact jaws, a blade, a pin extending through one pair of 130

jaws and the blade, and a detachable spring clip adapted to engage the jaws and having heads provided with cups which receive the ends of the pin, said clip being provided 5 with means for attachment to the blade.

9. In a switch of the character described, two pairs of jaws, each pair being provided with means enabling it to serve either as a blade carrying post or as contact jaws, a 10 blade, a pin extending through one pair of jaws and the blade, a detachable clip having spring arms which clasp the blade and spring arms extending from the blade clasping arms and provided with heads which 15 bear upon the jaws and retain the pin in place.

10. In a switch of the character described, two pairs of jaws, each pair being provided with means enabling it to serve as a blade carrying post or as contact jaws, each jaw 20 being provided with a tongue cut out from the metal thereof, a cross connection engaging the tongues to provide tension for the jaws, a blade, a loose pin passing through 25 one pair of jaws and the blade, and detachable means for retaining the pin in place.

11. In a switch of the character described, two pairs of jaws, each pair being provided with means enabling it to serve as a blade carrying post or as contact jaws, each jaw 30 being provided with a tongue cut out from the metal thereof, a cross connection engaging the tongues to provide tension for the jaws, a blade, a pin passing through one 35 pair of jaws and the blade, and a detachable clip having spring arms clasping the blade and other spring arms which engage the jaws and retain the pin in place.

12. In a switch of the character described, 40 contact blades provided with ears, and a tubular insulating cross bar having slots which receive the ears, and means within the tube for attaching the blades thereto.

13. In a switch of the character described, 45 contact blades having ears, a tubular insulating cross bar having slots which receive the ears, plugs driven into the tube, and screws within the tube which engage the ears and plugs and lock the blades to the cross 50 bar.

14. In a switch of the character described, contact blades having ears provided with shoulders, a tubular insulating cross bar having slots which receive the ears, the ends 55 of the slots being engaged by the shoulders, plugs in the tube, and screws engaging the ears and the plugs for the purpose set forth.

15. A switch of the character described 60 comprising two sets of jaws, each set consisting of two pairs of jaws, each set being provided with means enabling it to serve as blade carrying posts or as contact jaws, blades pivotally connected to one set of jaws, and an insulating cross bar having an insulated 65 connection to the blades and adapted

to engage the other set of jaws and act as a stop in the circuit closing position.

16. A switch of the character described 70 comprising two sets of jaws, each set consisting of two pairs of jaws, blades, pins passing through each blade and a pair of jaws, spring clips by which the pins are retained in place, and an insulating tubular cross bar having an insulated connection to the other ends of the blades. 75

17. A switch of the character described 80 comprising two sets of jaws, each set consisting of two pairs of jaws, blades, pins passing through each blade and a pair of jaws, spring clips clasping the blades and having spring arms which retain the pins in place, and an insulating cross bar having an insulated connection to the other ends of the blades.

18. A switch of the character described 85 comprising two sets of jaws, each set consisting of two pairs of jaws, each pair of jaws being provided with tongues cut out from the metal thereof, set screws engaging the tongues for the purpose set forth, blades, 90 means for detachably connecting the blades to one set of jaws, and an insulating tubular cross bar having an insulated connection to the other ends of the blades.

19. A switch of the character described 95 comprising two sets of jaws, each set consisting of two pairs of jaws, each pair of jaws being provided with tongues cut out from the metal thereof, set screws engaging the tongues for the purpose set forth, blades, 100 pins passing through each blade and a pair of jaws, spring clips by which the pins are retained in place, and an insulating tubular cross bar having an insulated connection to the other ends of the blades. 105

20. A switch of the character described comprising two sets of jaws, each set consisting of two pairs of jaws, each pair of jaws being provided with tongues cut out from the metal thereof, set screws engaging the 110 tongues for the purpose set forth, blades, pins passing through each blade and a pair of jaws, spring clips carried by the blades and having spring arms engaging the jaws to retain the pins in place, and an insulating 115 tubular cross bar having an insulated connection to the other ends of the blades.

21. In a switch of the character described, a blade, an auxiliary blade blanked out from sheet metal and folded upon itself, the attaching end of the auxiliary blade being provided with ears adapted to lie on opposite sides of the blade and being pivoted to the blade, and a spring housed in the auxiliary blade and acting to retain the auxiliary 120 blade in contact with the blade. 125

22. In a switch of the character described, a blade, an auxiliary blade blanked out from sheet metal and folded upon itself, the attaching end of the auxiliary blade being pro- 130

vided with a socket and with ears which lie on opposite sides of the blade and are pivoted thereto, and a spring housed in the auxiliary blade and acting to retain the auxiliary blade in contact with the blade.

23. In a switch of the character described, a blade, an auxiliary blade blanked out from sheet metal and folded upon itself, the attaching end of the auxiliary blade being provided with a socket and with ears which lie on opposite sides of the blade and are pivoted thereto, a spring comprising a coil having extended ends, and a pin passing through the coil and the walls of the socket, the ends of the spring bearing respectively against the under side of the blade and the bottom of the socket, whereby the auxiliary blade is retained in contact with the blade.

24. A switch of the character described comprising a blade, an auxiliary blade formed from thinner metal than the blade and folded upon itself to uniform thickness with the blade, the auxiliary blade being provided with a socket and ears which are pivoted to the blade, and a spring in the socket whereby the auxiliary blade is retained in contact with the blade.

25. A switch of the character described comprising a blade, an auxiliary blade pivoted thereto, and a spring socketed in the auxiliary blade for normally retaining it in contact with the blade.

26. A switch of the character described comprising a blade, an auxiliary blade having ears pivoted on opposite sides of the blade and a socket between the ears, the pivoted end of the auxiliary blade serving as a stop to limit the separation of the blades, and a spring in the socket acting to retain the edges of the blades in contact.

27. In a switch of the character described, two sets of jaws formed from strips of sheet metal bent to shape, each set consisting of two pairs of jaws provided with means enabling them to serve either as blade carrying posts or as contact jaws, blades pivoted to one set of jaws, auxiliary blades pivoted to the blades, and springs socketed in the auxiliary blades for retaining them in contact with the blades.

28. In a switch of the character described, two sets of jaws formed from strips of sheet metal bent to shape, each set consisting of two pairs of jaws provided with means enabling them to serve either as blade carrying posts or as contact jaws, a tension device in each pair of jaws comprising spring tongues cut out from the metal thereof and a set screw engaging the tongues, blades, a pin extending through each pair of jaws and a blade, detachable spring clips for retaining the pins in place, auxiliary blades pivoted to the blades, and springs socketed in

the auxiliary blades for retaining the edges of the auxiliary blades and the blades in contact.

29. In a switch of the character described, two sets of jaws formed from strips of sheet metal bent to shape, each set consisting of two pairs of jaws provided with means enabling them to serve either as blade carrying posts or as contact jaws, a tension device in each pair of jaws comprising spring tongues cut out from the metal thereof and a set screw engaging the tongues, blades, a pin extending through each pair of jaws and a blade, detachable spring clips for retaining the pins in place, auxiliary blades pivoted to the blades, springs socketed in the auxiliary blades for retaining the edges of the auxiliary blades and the blades in contact, an insulating tubular cross bar, and insulated means for connecting the blades to the cross bar.

30. In a switch of the character described, two sets of jaws formed from strips of sheet metal bent to shape, each set consisting of two pairs of jaws provided with means enabling them to serve either as blade carrying posts or as contact jaws, a tension device in each pair of jaws comprising spring tongues cut out from the metal thereof and a set screw engaging the tongues, blades, a pin extending through each pair of jaws and a blade, clips having spring arms which clasp the blades and other spring arms having heads which retain the pins in place, auxiliary blades pivoted to the blades, and springs socketed in the auxiliary blades for retaining the edges of the auxiliary blades and the blades in contact.

31. In a switch of the character described, two sets of jaws formed from strips of sheet metal bent to shape, each set consisting of two pairs of jaws provided with means enabling them to serve either as blade carrying posts or as contact jaws, a tension device in each pair of jaws comprising spring tongues cut out from the metal thereof and a set screw engaging the tongues, blades, a pin extending through each pair of jaws and a blade, clips having spring arms which clasp the blades and other spring arms having heads which retain the pins in place, auxiliary blades pivoted to the blades, springs socketed in the auxiliary blades for retaining the edges of the auxiliary blades and the blades in contact, ears extending from the blades, a tubular insulating cross bar having slots which receive the ears and means within the cross bar for attaching the cross bar to the blades.

In testimony whereof we affix our signatures.

ALEXANDER H. TRUMBULL.
TONJES A. BOTH.
